US00D615393S

(12) **United States Design Patent**
Cunningham, Jr. et al.

(10) **Patent No.:** US D615,393 S
(45) **Date of Patent:** ** May 11, 2010

(54) **ELECTRICAL BRANCH PANEL LOCKOUT**

(75) Inventors: **Phillip James Cunningham, Jr.**, Frisco, TX (US); **Scotty Ray Gross**, Fort Worth, TX (US)

(73) Assignee: **Specialty Electrical, LLC**, Fort Worth, TX (US)

(**) Term: **14 Years**

(21) Appl. No.: **29/315,373**

(22) Filed: **Jun. 19, 2009**

(51) **LOC (9) Cl.** 08-08

(52) **U.S. Cl.** D8/394

(58) **Field of Classification Search** D8/356, D8/371, 394-396; 24/570, 546, 563, 571; 248/74.2, 215, 227.1, 49, 300, 301, 316.7, 248/51, 489; D19/65, 56; 296/146.4

See application file for complete search history.

(57) **CLAIM**

The ornamental design for an electrical branch panel lockout, as shown and described.

DESCRIPTION

FIG. 1 is an isometric view of the electrical branch panel lockout in use on an electrical branch panel in accordance with the present invention;

FIG. 2 is an isometric view of the electrical branch panel lockout in accordance with the present invention; and,

FIG. 3 is a top view of the electrical branch panel lockout in accordance with the present invention.

The broken lines in the figures depict environment only and form no part of the claimed design.

1 Claim, 3 Drawing Sheets

FIG. 2

FIG. 3
